PAIR OF SPECTACLES

Anthony Shindler, Brookline, Mass., assignor to American Optical Corporation, Southbridge, Mass.

Filed Mar. 16, 1971, Ser. No. 124,997

Term of patent 7 years

Int. Cl. D16—06

U.S. Cl. D57—1 F

FIG. 1

FIG. 2

FIG. 3

FIG. 4.

FIG. 1 is a front elevational view of a pair of spectacles embodying my new design;

FIG. 2 is a top plan view thereof, the temples being broken away for convenience of illustration;

FIG. 3 is a side elevational view thereof, the opposite side being identical; and

FIG. 4 is a rear perspective view of the pair of spectacles.

The spectacles are shaded to indicate contrast.
I claim:

The ornamental design for a pair of spectacles, as shown and described.
